UNITED STATES PATENT OFFICE

EDMUND D. JANES, OF WATERBURY, CONNECTICUT, ASSIGNOR TO SCOVILL MANUFACTURING COMPANY, OF WATERBURY, CONNECTICUT, A CORPORATION OF CONNECTICUT

SEPARABLE FASTENER

Application filed November 19, 1930. Serial No. 496,695.

The object of this invention is to provide a resilient socket member of a snap fastener couple, with a collet encircling the spring elements in such way as to shield these elements against destruction of the snap action in the event of the article on which the socket is used being dropped, as on a floor, and stepped on, and which will take any unusual blow, and which also will protect the socket when the article on which it is placed undergoes laundering, especially when passed through a wringer, and which also will prevent distortion when there is any unusual lateral strain that would tend to unduly separate or pull away any of the various spring elements.

The invention consists of a socket member, of a snap fastener, composed of a barrel and a flange of one piece of metal, slotted partway through the barrel and entirely through the flange, to impart resilience to the socket member, and having a collet encircling and closed about the flange in such way as to permit resilient action in connecting the socket with a complementary stud member and disconnecting it therefrom, as I will proceed now to explain more fully and finally claim.

In the accompanying drawings illustrating the invention, in the several figures of which like parts are similarly designated, Figure 1 is a top plan view; Fig. 2 is a bottom plan view, and Fig. 3 is a vertical section of the spring member of the socket. Fig. 4 is a top plan view; Fig. 5 is a bottom plan view, and Fig. 6 is a vertical cross section of the collet. Fig. 7 is a vertical section of the spring element and collet assembled. Fig. 8 is a top plan view; Fig. 9 is a bottom plan view, and Fig. 10 is a vertical section of a cap for attaching the collet spring element to an object and at the same time presenting a finish to the attached parts. Fig. 11 is a vertical section of the parts attached to a piece of material.

The spring element, shown detached in Figs. 1, 2 and 3, may be of any usual or approved construction, in which there is a barrel 1, terminating in a laterally projecting flange 2, the barrel being slotted partway of its length, as at 3, and these slits extending entirely through the flange, as indicated

at 4, so as to impart resilience to the device.

The juncture of the barrel and flange has an offstanding bead 5 which forms a constricted spring neck adapted to engage the complementary portion of the stud member 55 (not shown) of the snap fastener couple, which stud member may be of any usual or approved construction.

The collet is composed of a top portion 6 provided with a hole 7 of a diameter larger than that of the barrel 1 of the spring element and also is provided with a circumferential flange 8.

As shown in Fig. 7, the collet when applied to the flange 2 encircles said flange, and its top 6 and flange 8 are closed about the said flange 2 above and below, respectively, in such manner as to be entirely free from the bead 5. Thus the collet is arranged in floating engagement with the flange 2 and allows sufficient space for the expansion of the spring element in the act of connecting and disconnecting the stud member.

The thus collected spring element is applied to an article, indicated by the part designated 9, Fig. 11, by inserting the barrel through the article and then closing the cap 10 over the barrel and mushrooming said barrel so as to afford a secure connection of the cap with the barrel.

This cap 10 may be of any approved construction, but the preferred construction, as shown in Figs. 8, 9 and 10, has the closed head 11 and the inturned slotted back 12, which slotted back engages the barrel above the bead 5.

When the parts are assembled as shown in Fig. 11, the collet takes up any strains placed upon the socket and thus prevents distortion. The collet, furthermore, in the case of any lateral pull or strain on the socket in coupling it with the complementary stud member, supports the socket member and thus prevents the undue pulling apart of the spring portions of the socket and so obviates the distorting and spoiling for future use of the said socket.

The collet, furthermore, when closed around the flange of the socket, acts as a shield which prevents the impairment or de-

struction of the snap action in case the article on which the fastener is used should be dropped on the floor and stepped on. It also protects the socket when the article on which it is mounted is subjected to laundering and especially to the laundry wringer. Moreover, by this arrangement, any unusual blow or pressure upon the socket will be taken up by the closed-in flange of the collet instead of by the resilient member itself.

I am aware that it is old to provide a collet on a socket member by means independent of the stud-engaging springs; and I am also aware that it is old to apply a collet to the turned-out edges of the spring socket, the application of the collet serving to turn out and clinch such edges; and I am also aware that it is old to provide a spring socket member having a lateral flange to which is applied a binding ring having a lower flange fitted beneath the offset portion of the flange of the socket and lying approximately flush with the surface of the socket flange and its stud-engaging portion, from which construction my socket and collet differ in that the top portion of the collet overlying the flange of the socket extends into close relation to the barrel of the socket and overlies the bead thereof while the lower portion of the collet underlies the flange and extends well below the bead; and I am also aware that it is old to apply a binder to a spring socket by placing the open end of the binder on the bottom of the lateral flange of the socket and then placing a ring above such flange and closing down the flange of the binder upon such ring, thus exposing the stud-engaging element of the socket to potential danger from blows instead of protecting it as in my construction.

Variations in the details of construction are permissible within the principle of my invention and the scope of the claims following.

What I claim is:—

45 1. A separable fastener socket, having a resilient barrel and a resilient flange extending laterally from its lower end, and a bead projecting inwardly into the barrel and downwardly below the flange at the juncture of the barrel and flange, and a collet having a portion overlying the top of the flange of the socket and extending into close proximity to the barrel, and having a flange 50 encircling the flange of the socket and curled inwardly thereunder, its inwardly curled portion extending below the bead, the collet being out of direct contact with said bead and substantially in floating engagement with the flange of the socket to permit normal expansion and contraction of the socket to facilitate its engagement with and disengagement from a complemental snap fastener stud, said collet serving to take up blows and strains upon the socket and maintain its ele-

ments in alignment and operativeness and free its bead from direct contact of blows.

2. A separable fastener socket, having a resilient barrel and a resilient flange extending laterally from its lower end, and a bead 70 projecting inwardly into the barrel and downwardly below the flange at the juncture of the barrel and flange, and a collet having a portion overlying the top of the flange of the socket and extending into close proximity to the barrel, and having a flange encircling the flange of the socket and curled inwardly thereunder, its inwardly curled portion extending below the bead, the collet being 75 out of direct contact with said bead and substantially in floating engagement with the flange of the socket to permit normal expansion and contraction of the socket to facilitate its engagement with and disengagement from a complemental snap fastener 80 stud, said collet serving to take up blows and strains upon the socket and maintain its elements in alignment and operativeness and free its bead from direct contact of blows, 85 combined with an attaching cap within which 90 the barrel of the socket is mushroomed, said cap engaging the barrel to secure the socket to an article.

In testimony whereof I have hereunto set my hand this 17th day of November A. D. 95 1930.

EDMUND D. JANES.
